SILENCER

Roland B. Bourne, West Hartford, Conn., assignor
to The Maxim Silencer Company, Hartford,
Conn., a corporation of Connecticut

Application December 26, 1940, Serial No. 371,603

15 Claims. (Cl. 181—57)

This invention relates to silencing devices and specifically to that type of silencing device in which gas and sound waves are conducted to or from a chamber by perforated or slotted conduits extending into each chamber and which may or may not overlap. In plural chamber devices the exhaust conduit from one chamber has been extended from within that chamber into the adjoining chamber to form the inlet conduit therefor. Such plural chamber silencers, in which the lengths of adjoining chambers should preferably be different in order to avoid series resonance phenomenon, have been much used in the past and give excellent results.

I have now found that these devices can be even further improved, and at the same time their expense of construction reduced, by providing a plurality of conduits passing through the partition separating the chambers; both conduits being substantially flush with the partition at one end, and one of them extending into one chamber and the other into the second chamber. By this means the length of pipe required for each conduit is reduced to about one-half, and a material increase in the sound attenuating qualities of the silencer and a decrease in the back pressure are both secured.

The invention will now be described in connection with the accompanying drawing, in which

Fig. 1 is a central longitudinal section through one form of silencer embodying the invention;

Fig. 2 is a section on line 2—2 of Fig. 1; and

Figs. 3 to 10 are similar pairs of views showing various modifications of the invention.

The device of Fig. 1 comprises a generally cylindrical casing 10 having an inlet header 11, an outlet header 12, and an internal transverse header 13 which divides the interior of the casing into two compartments 14 and 15. These compartments are preferably of unequal length in order to reduce the passage of unattenuated sound through the device due to longitudinal resonance within the chambers or conduits. An inlet conduit 16, having lateral escape openings in the form of a longitudinal slot 17 or an equivalent row of holes, extends inwardly through the header 11 into the interior of the compartment 14 to a point approximately midway between the headers 11 and 13. The inner end of the conduit 16 is open; so that the incoming pulsating gas is discharged freely from its open end, as well as to a certain extent through the lateral slot 17, into the compartment 14. A discharge conduit 18, having a longitudinal slot 19, picks up the gases in the compartment 15 and dis-

charges them to atmosphere through a suitable tail pipe. The transverse header 13 is furnished with at least two openings for the passage of exhaust gas from the compartment 14 to the compartment 15. From one of these openings there extends into the compartment 14 a conduit 20 which is provided with holes 21 preferably located at the half and quarter points for the purpose of preventing shock-excited resonance in this conduit. The conduit 20 extends about half-way into the compartment 14, terminating in an open end at a point approximately in line with the inner end of the conduit 16. From the other of the openings in the header 13 there extends into the compartment 15 a conduit 22 having lateral escape openings 23 and terminating in an open end approximately in line with the end of the conduit 18. In the embodiment shown, the cross-sectional area of each of the conduits 20 and 22 is half that of the conduits 16 and 18, so that the combined areas will be equal to the area of the latter conduits.

It will be seen that, of all the pulsating gas delivered into the compartment 14, half can pass out directly through the conduit 22, while the other half must reverse itself within the compartment and finally pass into the compartment 15 through the conduit 20. The net result is that the gas surges are effectively broken up and smoothed out before passing to the next compartment, and that the back pressure is reduced to a very low figure. Another benefit results from this construction. Any tendency towards longitudinal resonance in the compartment 14 is greatly reduced by the presence of the opening leading directly into the conduit 22 since this conduit has its beginning at the surface of the transverse header 13. It is in this region that pressure maxima must occur for every frequency for which the compartment 14 exhibits any longitudinal resonance tendency. Such a high acoustic pressure is prevented from building up to a point where objectionable resonance phenomena can occur by the free opening into conduit 22. In a similar manner the conduit 20 acts as an anti-resonating leak for the chamber 15. Strictly speaking the conduits associated with the transverse header 13 are only a part of the anti-resonance system. The chamber 15 acts together with the conduit 22 to prevent resonance in the compartment 14, while the chamber 14 and the conduit 20 act together to prevent resonance in the chamber 15. The conduits 20 and 22 are sufficiently long and have enough acoustic resistance so that the system as a whole does not func-

tion as a compound resonator. Devices of this type are particularly adaptable for silencing internal combustion engines having port exhausts, air compressors, and the like.

Figs. 3 and 4 show a similar device, except that the internal transverse header is positioned midway along the length of the cylindrical casing. This embodiment yields a symmetrical structure and is particularly adaptable to long discharge or suction lines. Each half of the device acts both as a pulse and sound attenuator in itself and also as a resonance preventor for the other half of the silencer. The structure in this embodiment being identical with that of Fig. 1 the same numerals have been used in the two cases.

Fig. 5 shows another embodiment of the invention comprising an inlet chamber 24 and an outlet chamber 25 separated by the partition 26. The inner connection 27 in this case discharges the incoming pulsating gas in the chamber 24. There are two outlet conduits connecting the chamber 24 with the chamber 25; the perforated conduit 28 extending from the header 26 into the chamber 24, and a pipe 29 (here shown as unperforated) extending from the header 26 into the chamber 25. In this embodiment the total cross-sectional area of the two conduits 28, 29 equals that of the inlet conduit 27, but the area of the conduit 28 is appreciably larger than that of the relatively short conduit 29. This construction is advantageous where it is desired to improve the high frequency attenuation of the device. The slotted outlet conduit 30 extends from the outlet header to a point in adjacency to the internal transverse header 26.

Another embodiment of the invention is shown in Figs. 7 and 8. This device functions as previously described, but differs from the devices of the preceding figures in that the chambers 31 and 32 have overlapping conduits 33, 34 and 35, 36, respectively. The chambers 31, 32 are not necessarily the same size. In this form of device one or more of the connections can be continued to the opposite header, so that there is no longer any open end, provided that the area of the laterally opening slot is sufficient to permit the escape of all the gas without injuriously increasing the back pressure.

Fig. 9 shows a device embodying the principles of the invention in which are employed three chambers 37, 38 and 39, which are preferably all of different lengths and are formed within the casing by the transverse headers 40 and 41. The two conduits 42 and 43 associated with the header 40 are shown as spaced along a vertical plane, while the conduits 44, 45 associated with the header 41 are spaced apart one from the other in a horizontal plane. This arrangement prevents direct transmission of gas and pulses from one conduit to another without expanding into the volume of the chamber 38. All conduits are furnished with lateral escape openings with slots and holes to prevent resonance in the conduits themselves and to assist in the breaking up of the gas surges.

I claim:

1. A silencer comprising a casing, a partition within the casing dividing it into two chambers, a conduit extending from the partition into one of said chambers only, a second conduit extending from the partition into the second named chamber only, and conduits for the introduction of gas into one of the chambers and for the exhaust of gas from the other of said chambers.

2. A silencer in accordance with claim 1, at

least one of said conduits having lateral escape openings formed along its length.

3. A silencer comprising a casing, a partition dividing said casing into an inlet chamber and an outlet chamber, an inlet conduit extending into the inlet chamber, an outlet conduit extending from the interior of the outlet chamber, an intermediate conduit extending from a point in the inlet chamber through but not appreciably beyond the partition and opening into the outlet chamber, a second intermediate conduit extending from the interior of the outlet chamber through but not appreciably beyond the partition and opening into the inlet chamber.

4. In a silencer having an expansion chamber, two outlet conduits, one extending into the interior of the chamber and the other extending from a bounding wall of said chamber to a point remote from said bounding wall and outside said chamber.

5. A silencer of the type having two chambers in series separated by a partition, characterized by two separate connecting conduits between the chambers each being inaugurated at and opening through said partition, and extending one into the interior of one of the chambers and the other into the interior of the other of said chambers.

6. A silencer in accordance with claim 3 wherein at least one of the interiorly disposed conduits is furnished with lateral escape openings disposed along its length.

7. A silencer in accordance with claim 3 wherein the open ends of the conduits within the chambers terminate at a point substantially midway along the length thereof.

8. A silencer comprising an inlet chamber and an outlet chamber, an inlet connection in said inlet chamber and an outlet connection in said outlet chamber, said inlet and outlet chambers being separated by a partition having at least two apertures therein, a conduit leading from the interior of said inlet chamber to but not beyond one of said apertures, a conduit inaugurated at the other of said apertures and extending into the interior of said outlet chamber, and an outlet conduit extending from the interior of said outlet chamber to said outlet connection.

9. A silencer comprising a casing divided into two chambers by a partition, an open ended conduit extending from the interior of one of said chambers through said partition into the other of said chambers but not extending into it, an open ended conduit extending from the interior of the second named chamber through the partition and opening but not extending into the first named chamber, the cross-sectional area of one of said conduits being appreciably larger than that of the other of said conduits.

10. A silencer comprising a casing, a partition within the casing dividing it into an inlet compartment and an outlet compartment, said partition having two apertures therein, an inlet connection in said casing communicating with said inlet chamber, an outlet connection in said casing communicating with said outlet chamber, an inlet conduit having lateral escape openings disposed along its length extending from said inlet connection into the interior of said inlet chamber and terminating at a point in adjacency to said partition, a conduit having lateral escape openings along its length extending from a point in adjacency to the inlet end of the inlet chamber to one of said apertures but not beyond it, a conduit having lateral escape open-

ings disposed along its length extending from the other of said apertures in said partition to a point in adjacency to the outlet end of said outlet chamber, and a conduit having lateral escape openings along its length extending from a point in adjacency to said partition to said outlet connection.

11. A silencer comprising a casing, a pair of transverse partitions within the casing dividing it into three compartments, a pair of conduits associated with each of said partitions each conduit extending from the partition in one direction only and the conduits associated with each partition extending therefrom in opposite directions into adjacent compartments.

12. A silencer having an expansion chamber, parallel gas passages through a wall of said chamber, one of said passages being inaugurated within the chamber and extending through but not beyond the wall and another of said gas passages being inaugurated at the wall and extending an appreciable distance therebeyond.

13. A silencer comprising a casing, a transverse partition within said casing dividing it into two chambers, said partition being provided with a pair of apertures, open ended conduits one associated with each of said apertures and extend-

ing therefrom into one of the chambers, the two conduits extending from the partition in opposite directions respectively into the two chambers.

5 14. A silencer comprising casing members forming a plurality of chambers, a pair of connections in parallel between the chambers one extending from a point of high acoustic pressure in one chamber to a point of high acoustic velocity for standing wave systems extending longitudinally of the second chamber, and the other extending from a point of high acoustic pressure in the second chamber to a point of high acoustic velocity for standing wave systems extending longitudinally of the first chamber, and means for introducing a pulsating gas into one of said chambers and for conducting the gas from the second chamber.

10 15. A silencer comprising casing members forming a pair of chambers, conduits in each chamber laterally offset one from the other and one forming an inlet and the other an outlet, and additional connections between one end wall of each chamber and an intermediate interior point of the other chamber.
